UNITED STATES PATENT OFFICE.

ORAN W. MONTGOMERY, OF LAKEWOOD, OHIO.

PORTABLE ELECTRIC LIQUID HEATER.

1,425,034.

Specification of Letters Patent. Patented Aug. 8, 1922.

Application filed May 21, 1921. Serial No. 471,305.

To all whom it may concern:

Be it known that I, ORAN W. MONTGOMERY, a citizen of the United States, residing at Lakewood, in the county of Cuyahoga, in the State of Ohio, have invented certain new and useful Improvements Relating to Portable Electric Liquid Heaters.

The objects of my invention are first to provide, a small compact appliance that can 10 be immersed in any vessel in which it is desired to heat a quantity of liquid, and second to provide an efficient heating means, together with such features of construction as will insure safety to the user.

15 Referring to the drawings, a system of numerals is employed in which corresponding numerals refer to corresponding parts, as detailed by the systematic order of reference employed in the specification.

20 Fig. 1, shows a cross section of my device taken as a vertical side view.

Fig. 2, shows a plan view of the interior layout.

25 Fig. 3, shows a plan view of the exterior of the device minus the connecting wires and grounding attachment.

Proceeding with the description of Fig. 1, 1, is a case of such design as will enclose and protect the heating unit which is placed 30 within.

2, is a tube and is secured to the plate 3, by means provided, this tube serves as a handle for the heater, as well as a conduit for conveying the current supply wires to 35 the heating unit. The plate 3, is provided with a series of openings as shown under Fig. 3 through which liquid being heated may circulate from the interior of the heater to the container holding the supply of liquid.

40 This plate is secured to the case 1, by means of the screws 4.

11 and 12 are carbon or metallic discs and are suspended within the case from the plate 3, by means of the insulator 6, an insulating 45 washer 13, separates the two discs and provides a gap which will permit a film of water to lie between. It is by this construction that I utilize the resistive characteristics of water or other liquids to serve as 50 a heating element. As the current attempts to pass through the water it becomes heated and forcing its way outwardly is displaced by other colder water entering the heater from the vessel holding the liquid to be 55 heated.

Disc 12 is connected to wire 10, of the

electric circuit by means of the bolt 7, which passes through the insulator 6.

Disc 11, is connected to the other wire of the circuit by means of the washer 8, to 60 which the wire may be connected by any suitable means. 5 is a hard rubber or other insulative cap which covers the electrical connections at the base of the tube 2. At the top of the tube 2 is inserted the bushing 65 14, which serves to prevent abrasion of the wires entering at this point.

I have found it excellent practice to fill the part of the tube surrounding the wires with a vitreous or other cement which will 70 prevent water from entering.

15 is a flexible cable or chain which serves as a detachable ground connector, and is provided with a clip 16, by which attachment to any permanent ground, such a water pipe 75 or faucet is made by drawing the cable through the clip. The object of the ground connection is to neutralize the effects of electrification to which the heater and liquid is subject while the current is passing 80 through the water during the process of heating.

Having described my invention, what I claim is,

1. A portable electric liquid heater comprising a pair of annular electrodes, spaced and insulated apart, a case for receiving said electrodes, means for insulating said electrodes from said case, a plate covering said case, a series of apertures in said plate allowing for liquid circulation inwardly and outwardly of said case, means for fastening said plate to said case, a handle secured vertically to said plate, said handle serving as a protective support to an insulated conductor 85 adapted to supply current to said heating electrodes, substantially as described for the purpose set forth.

2. A portable electric liquid heater comprising a pair of annular electrodes spaced and insulated apart, a case for receiving said electrodes, means for insulating said electrodes apart, means for connecting each of said electrodes to a source of electric supply, a plate covering said case, a series of 100 apertures in said plate, means for suspending said electrodes within said case, means for forming a gap between said electrodes and means for passing a quantity of water from an external source into the gap between 105 the electrodes, and means for passing the water out of said case as it becomes heated,

substantially as described for the purpose set forth.

3. A portable electric liquid heater comprising an electric heating element, a flat case for receiving said heating element, a plate covering said case, means for fastening said plate to said case, a handle secured vertically to said plate, a pair of wires passing through said handle and terminating at 10 means for connecting said wires to said heating element within said case, substantially as shown and described.

4. A portable electric liquid heater, comprising a pair of annular electrodes, spaced 15 and insulated apart, a case for receiving said

electrodes, a means for insulating said electrodes from said case, a plate covering the top of said case, a series of apertures in said plate allowing for liquid circulation inwardly and outwardly of said case, a handle secured vertically from said case, said handle serving as a protective support to the insulated conductor adapted to supply current to said heating units, a flexible grounding attachment, provided with a clip by which the heater may be grounded, substantially as described. 20 25

Signed at Lakewood, Ohio on this 19th day of May 1921.

ORAN W. MONTGOMERY.
